UNITED STATES PATENT OFFICE.

HENRY A. OWEN, OF WHITINSVILLE, MASSACHUSETTS, ASSIGNOR, BY MESNE ASSIGNMENTS, TO DRAPER CORPORATION, OF HOPEDALE, MASSACHUSETTS, A CORPORATION OF MAINE.

LOOM FEELER-MOTION.

1,291,104.

Specification of Letter Patent. Patented Jan. 14, 1919.

Application filed July 12, 1917. Serial No. 180,032.

To all whom it may concern:

Be it known that I, HENRY A. OWEN, United States citizen, residing in Whitinsville, Massachusetts, have invented the following described Improvements in Loom Feeler-Motions.

This invention is an improvement in side slipping feeler motions for automatic looms such as shown in United States Letters Patent No. 1,258,727, March 12, 1918, and No. 1,278,732, September 10, 1918, and concerns more especially the construction and relative arrangement of the trip members in said motion or in any side slipping feeler motion, by means of which the feeler arm or bell crank structure engages and trips or operates the call-transmitting element which brings about the change in the loom or its stoppage. The accompanying drawing illustrates a preferred embodiment of the invention and the method of applying the same to practical use.

Figure 1 is a side elevation of the apparatus as viewed from the front of the loom; Fig. 2 a top plan;

Fig. 3 a cross section on enlarged scale on line III of Fig. 2; and

Fig. 4 is an enlarged detail plan of the trip members.

The feeler motion is carried by a bracket plate 1 supported on the breast-beam or an extension. The feeler arm or bell crank structure 2 which carries the side slipping feeler tip 3 is fulcrumed at 4 on a forwardly yielding feeler carrier 5 and is itself held yieldingly in a normal or non-calling position on said lever by a light adjustable spring 6 which draws it against the end of a small set-screw 7 constituting an adjustable stop therefor. The spring 6 and the set-screw 7 are both carried by the carrier 5 and the latter is pivoted at 8 to the bracket plate 1 and urged rearwardly of the loom and against an abutment stop 9 by means of a spring 10.

On every other beat-up of the lay, the bobbin or other weft carrier in the shuttle engages the feeler tip and through the latter and its connections, presses the feeler carrier forwardly. If the condition of the wound mass of weft on the bobbin, not closely approaching exhaustion, the feeler tip and arm will recede under this pressure without turning on the pivot 4; that is to say, it will preserve its non-calling position as indicated in Fig. 2, being held thereto by the engage-

ment of the tip with the weft, but if the weft is depleted to a predetermined extent, the tip 3 will slip thereon or therewith, and the feeler arm will then recede in a turned position, such as indicated in Fig. 4. The turning movement will be observed to arise from the non-alinement of the direction of thrust on the tip with the pivotal support (4) of the feeler arm on its carrier (5) and it is utilized to shift the feeler tip 11 into position to strike, as it recedes, a corresponding abutment 12 on one of the call-transmitting elements such as the lever transmitter 13, and thereby transmit the call to the changing or controlling mechanism. The trip 11 on the feeler arm is formed as a separate part of hardened steel with a round stem adjustably set-screwed in a socket in the arm and the abutment 12 which is similarly formed of hardened steel and set-screwed in the transmitter 13.

The mechanism as thus far described is similar to that of the aforesaid Patent No. 1,258,727, March 12, 1918.

The present improvement relates to the particular construction of the forward tripping end of the feeler arm, and of the abutment of the transmitter, and to their relation to each other. As shown in Figs. 2, and 4, the tripping end A, of the feeler arm extends forwardly so that normally (that is when the feeler is at rest) the abutment 12, of the transmitter is in the side slipping path of the tripping end. This normal condition is illustrated in Fig. 2. By reason of this relation, when the feeler tip slides sidewise along the bobbin, as illustrated in Fig. 4, the forwardly extending tripping end A, of the feeler arm encounters the abutment 12, of the transmitter which thus acts as a stop to limit the side slipping movement of the feeler arm and tip. Accordingly, there is no need for a special extraneous abutment to limit the side slip of the feeler arm such as is provided in each of the aforesaid patents No. 1,258,727, and No. 1,278,732.

The feeler arm has a push shoulder B, back of the tripping end A, and extending at an angle thereto. During the normal position of rest of the feeler arm and of the transmitter, and also during the forward and back movement of the feeler and the feeler carrier while sufficient weft is in the shuttle to prevent the side slip of the feeler tip, the abutment 12, is out of register with

the push shoulder and out of its back and forth path of travel. When, however, the feeler arm slips sidewise and the tripping end A, of the feeler arm is stopped by the 5 abutment 12, the push shoulder B, is brought into pushing position relatively to the abutment as illustrated in Fig. 4. As there shown the push shoulder is positioned immediately behind the abutment so that on the 10 ensuing forward movement of the feeler and its carrier the push shoulder acts upon the abutment thereby moving the transmitter 13, so as to set into action the weft replenishing train of mechanism.

15 The abutment 12, as shown, is wedge-shaped with a sharp edge facing the angle between the tripping end A, of the feeler arm and the push shoulder B, into which it is adapted to enter and seat on the side slipping feeler arm as shown in Fig. 4. This 20 manner of engagement between the tripping end of the feeler and the abutment not only eliminates the need for a special abutment to limit the slip-turning movement of the 25 feeler, such as shown in the patents above referred to, but also improves the action and reduces wear on the contacting edges. The same effect will be attained regardless of whether the feeler arm or the transmitter 30 carries the push shoulder and whether the engaging parts have the particular shape illustrated, because one will in any event constitute an abutment surface for the other. It will also be apparent that the particular 35 character of the support for the feeler and the dispositions of the parts permitting it to yield to the bobbin and to slip on the weft, and also the instrumentalities whereby the call is transmitted, are all quite inconsequential to the characteristics of tripping means 40 just described. The said call-transmitting means, in the present case, comprises the transmitter 13 fulcrumed at 14 on the bracket plate 1 and kept in inactive position

by a spring 15. The operating end of this 45 lever is provided with a cam surface, see detail Fig. 3, whereby it co-acts with a corresponding surface on a second lever 16 to swing the latter vertically and thereby cause its extended finger to lift or shift the dog 17 50 into or out of the path of the weft hammer 18 according to the design of the calling agencies and as will be understood by those skilled in the art.

Claims:

1. A loom having a feeler motion comprising, in combination, a feeler carrier movable back and forth on the loom, a side-slipping feeler arm movable on the carrier and having its tripping end extending forwardly and a push shoulder at an angle to said tripping end, and a transmitter having an abutment normally standing in the side slipping path of the tripping end of the feeler arm and serving to limit the extent of 60 the side slip, said abutment being normally out of the path of the back and forth movement of the push shoulder, said push shoulder being brought into pushing position relatively to said abutment by the side- 65 slip movement of the feeler arm. 70

2. A loom having a feeler motion comprising, in combination, a feeler carrier movable back and forth on the loom, a side-slipping feeler arm movable on the carrier and having its tripping end extending forwardly, a transmitter having an abutment normally occupying a position to limit the extent of 75 the side slip of the feeler arm, and one of said parts (the feeler arm or the abutment) 80 having a push shoulder which is normally idle but which is brought into active position when the feeler arm slips to effect engagement between the feeler arm and the abutment as the feeler carrier moves forward. 85

In testimony whereof, I have signed this specification.

HENRY A. OWEN.
